UNITED STATES PATENT OFFICE.

JOSEPH T. CRAW, OF JERSEY CITY, NEW JERSEY, ASSIGNOR OF ONE-HALF TO ROBERT P. BROWN AND EDWARD L. BAILEY, OF PHILADELPHIA, PENNSYLVANIA.

BOX-SEALING MACHINE.

SPECIFICATION forming part of Letters Patent No. 684,805, dated October 10, 1899.

Application filed March 14, 1899. Serial No. 708,991. (No model.)

To all whom it may concern:

Be it known that I, JOSEPH T. CRAW, of Jersey City, in the county of Hudson and State of New Jersey, have invented a new and 5 useful Improvement in Means for Sealing Paper Boxes, of which the following is a full, clear, and exact description.

The object of my invention is to so seal the flaps of paper boxes that said boxes will be 10 siftless, thus particularly adapting them to hold sugar or other fine or granular material, and, further, to accomplish such object by a very simple, inexpensive, and readily-applied means.

15 Another object of the invention is to provide means for applying a sealing compound, such as glue or gum, to the top and bottom surfaces of a sealing-strip or to a series of connected strips capable of ready separation.

20 A further object of the invention is to so construct a form or casing that one or a number of empty boxes or filled boxes may be received and held therein and the sealing-strips simultaneously applied to all of the boxes at 25 one end and whereby all of the boxes in the casing at one end and the flaps of all of the boxes at such end may be simultaneously and siftlessly sealed.

Another object of the invention is to so construct the individual devices that they may 30 be used either alone or collectively, as they preferably are, and be attended by a single person.

The invention consists in the novel construction and combination of the several parts, as 35 will be hereinafter fully set forth, and pointed out in the claims.

Reference is to be had to the accompanying drawings, forming a part of this specification, 40 in which similar characters of reference indicate corresponding parts in all the figures.

Figure 1 is a side elevation of the device adapted to apply the adhesive material to the strips and a side elevation of a portion of the 45 table upon which said device is supported together with a side elevation of a form or casing adapted to hold the paper boxes to be sealed. Fig. 2 is a plan view of the devices shown in Fig. 1. Fig. 3 is a plan view of the 50 connected sealing-strips having adhesive ma-

terial applied thereto. Fig. 4 is an enlarged sectional view of the device for applying the adhesive material, taken through a portion of the glue-pot and longitudinally through connected sealing-strips and the supports for 55 the glued or gummed strips and also transversely through the rolls for applying the gum or glue, the section being taken practically on the line 4 4 of Fig. 5. Fig. 5 is a transverse section taken practically on the line 5 5 60 of Fig. 4. Fig. 6 is a perspective view of the form or casing adapted to receive the boxes, illustrating empty boxes contained in said form or casing ready to receive a sealing-strip at one end. Fig. 7 is a plan view of the form 65 or casing shown in Fig. 6, illustrating the application of the sealing-strip to the inner flaps of the box, a portion of the sealing-strip being broken away. Fig. 8 is an end view of the form or casing, partly in section, illustrating 70 the flaps of the boxes shown in Figs. 6 and 7 as held in sealing engagement with the sealing-strips passed over the boxes and the application of weighted wings to the outer flaps of the boxes. Fig. 9 is a perspective 75 view of an empty box located upon a block, the flaps at the end to be sealed being in the position they occupy when an empty box is placed in the form or casing. Fig. 10 is a perspective view of a box sealed at both ends in 80 the improved manner; and Fig. 11 is a perspective view of the sealed end of a box, one of the outer flaps being broken away to disclose the sealing-strip.

A represents a table supported by suitable 85 legs 10, and B a glue pot or trough located upon said table, preferably at one side near one end. The pot B is provided with a double bottom 11, forming a steam-space 12, and at the central portion of each side of the glue 90 pot or trough an angular or L-shaped stand 13 is constructed, the vertical member of each standard having a vertical slot 14 made therein and the horizontal member a horizontal slot 15; but the slots in the members do 95 not connect. A box 14^a is held to slide in the slot or opening 14 of each standard, and said boxes are raised and lowered through the medium of adjusting-screws 14^b. A box 15^a is held to slide in the horizontal slot 15 of the 100

standard, and said boxes 15^a are adjusted through the medium of screws 15^b or their equivalents, as illustrated in Fig. 1.

The trunnions 16 of a roller 17 are mounted 5 in the boxes 14^a, said roller turning partially within the trough or glue-pot, as shown best in Fig. 4. This roller 17 is usually made solid, and its periphery is corrugated or provided with a series of annular grooves 18, as shown 10 in Fig. 5, and the material 19, forming the peripheral surface of the roller, is made of felt, rubber, leather, or other material that is a good conductor of glue.

The scraper or doctor 20 is in the form of 15 a roller, and the trunnions of this roller are mounted in the boxes 15^a. The peripheral surface of the doctor-roller 20 is corrugated or provided with annular grooves, and said grooves in the doctor-roller alternate with the 20 grooves in the take-up roller 17 for the glue. The roller 20 prevents the glue from buckling at the upper face of the roller and is intended to govern the amount of glue that is to be presented to the strips to which application 25 is to be made. A roller 21 is located above the take-up roller 17. The upper roller 21 is likewise provided with a corrugated periphery or annular grooves 22, the grooves in the peripheries of the two rollers being made to 30 coincide. The upper roller 21 is hollow, and its peripheral surface 23 is made usually of the same material as the peripheral surface 19 of the lower roller 17. A bushing 24 is placed centrally in each end of the upper roller 35 21, and the shaft 25 for said upper roller extends out through the bushings and is hollow and perforated within the roller, as shown in Fig. 4. The shaft 25 forms a continuation of tubular side arms 26, and said side arms are 40 connected by swing-joints 26^a with pipes 27 and 27^a, supported by standards 28, said standards being secured to the table near the rear portion of the glue pot or trough. The pipe 27 extends downward through the table and 45 beneath it to a connection with a steam-supply pipe 29, which latter pipe is made to enter the steam-chamber 12 of said glue pot or trough, while the pipe 27^a is an exhaust-pipe and after being carried through the table is 50 disposed in any suitable or approved manner. Thus it will be observed that the upper roller may be raised and lowered, and said upper roller 21 when in its lower position is adapted to distribute glue upon the upper face of a 55 strip or tape 35 of paper fed from any suitable source of supply, while the lower roller distributes glue upon the under face of the strip. The strip or tape of paper, as shown in Fig. 3, is divided by perforations *b* into a 60 number of small strips 35^a, each of said strips being of corresponding size to the area of the end portion of a box to be sealed.

The paper is supported before it reaches the gluing-rollers by means of a table 29^a, 65 suitably sustained, and after the paper is coated with glue it is supported by a horizontal rack 30, which rack is supported from the

sides of the glue pot or trough through the medium of uprights 31. The rack 30 consists of two side bars *a*, that are removable from 70 the uprights, and cross-bars *a'*, which cross-bars may be readily attached to the side bars or made to turn therein, or they may simply rest on said side bars, so that the rack may be removed when necessary, placed in hot 75 water, and thoroughly cleaned from any glue that may adhere thereto.

Standards 32 are secured to the sides of the glue pot or trough between the rack 30 and the rollers 17 and 21. These standards 80 are connected by cross-bars 33, (shown in Fig. 4,) and each cross-bar 33 is provided with a series of fingers 34. These fingers enter the grooves in the upper and in the lower gluing-rollers and at their free ends come quite 85 close together, and the opposing surfaces of the fingers at their free ends are more or less beveled. The glue-coated material passes between the fingers and is prevented by said fingers from clinging to the rollers and being 90 carried around by them.

A belt 36 is located opposite the inner end of the glue pot or trough, as shown in Fig. 2. This belt is made to turn over rollers 37, extending upward through suitable openings in 95 the table, the top strand of the belt being about flush with the table and the lower strand being below the table, as shown in Fig. 1. The trunnions of the rollers 37 are journaled in suitable bearings 38, secured to the under 100 surface of the table. A second belt 39 is located upon the table parallel to the belt 36, which latter belt is made to pass over rollers 40, extending up through suitable openings in the table, the trunnions of the rollers 40 105 turning in bearings 41 at the under surface of the table. The two belts 36 and 39 move in opposite directions, the upper strand of the belt 36 traveling toward the gluing mechanism, while the upper strand of the belt 39 110 travels away from the gluing mechanism, as indicated by the arrows in Fig. 2.

A form or casing C is used in connection with the gluing device. This form or casing C, as shown in Figs. 6, 7, and 8, usually consists, mainly, of a base 42 and sides 43, secured to the base in such manner that the space between the sides will snugly fit and receive a box whose ends are to be sealed, and each form or casing is generally made of such 120 length that it will accommodate five boxes. A latch 44 is located at each end of the form or casing C, being pivoted to the end portion of one side and arranged to engage with a keeper 45 on the end portion of the opposite 125 side. The form or casing is provided with a cover made in two sections 46 and 47, the section 46 being wider than the section 47, and each section is provided with a weight 48, secured to its upper surface. The sections of 130 the cover have a hinged connection with opposite side faces of the form or casing C, as is clearly shown in Fig. 8, and may be carried to an upright position, as shown in posi-

tive lines in Fig. 6 and in dotted lines in Fig. 8, or the sections of the cover may be carried to a horizontal position, thus closing the upper surface of the form or casing, as illustrated in Fig. 8.

The form or casing C is made in two sizes, the difference being in the height. The higher form or casing is adapted to receive empty boxes, one end of which is to be closed, while the lower style of form or casing is adapted to receive boxes that have been filled. When an end of an empty box is to be closed, a block E is introduced into said box. This block is longer than the box, including the width of the flaps at one end, as is shown in Fig. 9. When a block has been placed in an empty box, the inner flaps 49 and 50 of the box being treated are folded down upon the body of the box by the fingers of the operator, the outer flaps 51 and 52 being left in a vertical position. This disposition of the flaps is made only at one end of the box that is to be sealed, as the block holds all the flaps at the other end of said box in a vertical position. The boxes and their flaps are introduced into a form or casing adapted to receive them, the wings or sections of the cover of the form or casing being open, as shown in Fig. 6, and the form or casing into which the empty boxes and their blocks are placed is usually located a slight distance from the belt 39 and in front of the rack provided for the coated strips, as shown in Figs. 1 and 2. When five boxes or more and their blocks have been placed in a form, they will completely fill said form or casing, it being understood that when a form is prepared to receive boxes one of the latches is left closed, while the other latch is opened. Upon closing the opened latch all of the boxes in the form will be held in close contact and cannot possibly shift. The operator will now reach up to the tray 30 and will remove therefrom five connected strips, which have been coated with glue upon both faces. These connected strips are laid upon the folded flaps 49 and 50 at the uppermost ends of the boxes, and each strip 35^a is of such size that it will extend not only to an engagement with the side edges of a box, but likewise to a positive engagement with the inner faces of the upright outer flaps 51 and 52 of the box. The coated strips having been placed in position on the boxes the narrower section 47 of the cover is carried downward, taking with it, for example, the outer flaps 51 of the boxes, pressing said outer flaps firmly against the upper faces of the sealing-strips 35^a. The operator may now readily see whether or not the flaps are properly connected with the sealing strips. Being satisfied on this point, the wider section 46 of the cover is pressed downward, carrying downwardly with it the outer flaps 52, as shown in Fig. 8. Each set of flaps at each end is so cut that when a set of flaps is folded said flaps will not overlap, but their opposing edges will be brought quite

close together, as shown in Fig. 10. Thus it will be observed an upper and a lower flat surface are provided between which the sealing-strip is placed. Thus a sealing-strip 70 coated with glue upon both sides rests between the inner and outer end flaps of the box, gluing said flaps together, and not only closing any space that may exist where the flaps meet, but also where the outer flaps connect with the body of the box, rendering the box perfectly siftless when sealed.

When the empty boxes in one form have been sealed at one end, said form is carried near to the inner end of the belt 39 and left 80 standing for awhile, and a second form that is substituted for the form removed is filled with empty boxes with their blocks, and the operation of closing the ends of said boxes is accomplished in the manner above stated. 85 When the second form has been filled and the upper ends of the boxes therein sealed, the latch 44 next to the belt 39 on the form first filled is opened, and the boxes and blocks are forced out of the form first filled onto the belt 90 39. The second form is then carried toward the belt, and the form first manipulated is removed from near the belt and is again carried into position to be filled. The boxes and the blocks contained therein are carried by the 95 belt 39 to the person whose duty it is to fill the boxes with material. This person removes the blocks from the boxes and places them on the belt 36, which carries the blocks toward the gluing device and within easy 100 reach of the person superintending the sealing of the empty boxes. The filled boxes may be placed upon the belt 36 and carried toward the gluing device or they may be carried toward a second gluing device at the opposite 105 end of the table. However, after the boxes have been filled they are cared for by an attendant who places them in a form adapted to receive them, the inner flaps being turned down upon the material in the boxes, and 110 this person will conduct the operation of sealing five filled boxes at one time and in the same manner as the person who seals the ends of five empty boxes at one operation.

The material that is fed to the rollers of 115 the gluing device is in tape form, each tape consisting, preferably, of five or more sealing-strips, and any suitable mechanism may be employed for revolving the rollers, and after a strip has been drawn between the rollers 120 said rollers will revolve in contact with each other, and in this manner glue will be transferred from the lower roller to the upper roller in sufficient quantities to properly coat the tape of sealing-strips. It will be understood 125 that the lower roller may be rotated by a band X, operated from any suitable source of power, or by hand, if desired, the said roller imparting motion to the upper roller by means of intermeshing cogs Y, and any suitable means 130 may be employed for imparting motion to the conveyer-belts 36 and 39.

Having thus described my invention, I claim as new and desire to secure by Letters Patent—

1. In a machine for the purpose described, 5 a glue-pot provided with L-shaped standards each formed with a vertical and horizontal slot, a take-up roller journaled in boxes slidably fitted in the vertical slots whereby the said roller may be raised and lowered, and a doctor-roller journaled in boxes slidably fitted in the horizontal slots whereby said doctor-roller may be brought in contact with the take-up roller when the latter is at different elevations, as set forth.
- 15 2. In a machine for the purpose described, a glue-pot, a take-up roller mounted to rotate partially within and partially without said glue-pot, and formed with a series of annular grooves on its periphery, and a doctor-roller 20 mounted adjacent said take-up roller and formed with a series of annular grooves on its periphery alternating with the grooves in the take-up roller, as set forth.
- 25 3. In a mechanism for sealing the flaps of paper boxes, a glue-pot, a take-up roller mounted to revolve partially within and partially without the glue-pot, a doctor for said take-up roller, a second roller located above and arranged for contact with the take-up 30 roller; means, substantially as described, for heating the upper roller, and guide-fingers converging at a point in front of and between said rollers, the material to be coated being adapted to pass between said fingers when leaving said rollers, as described.
- 35 4. In a mechanism for sealing the flaps of paper boxes, a steam-heated glue-pot, a take-up roller mounted to revolve partially within and partially without said glue-pot, the periphery of said take-up roller being provided with annular grooves, a similarly-grooved hollow roller located above the take-up roller and adapted for engagement with the upper 40 surface of the same, a doctor for the take-up

roller, means for supplying steam to the glue-pot and to the interior of the upper roller, and guide-fingers arranged to receive the material passed between and coated by said rollers, as set forth.

5. In a machine for the purpose described, 50 a glue-pot, a take-up roller mounted to rotate partially within and partially without said glue-pot and formed with a series of annular grooves on its periphery, and a second roller arranged for engagement with the take-up 55 roller and formed with a series of annular grooves in its periphery coinciding with the grooves in the take-up roller, as set forth.

6. In a machine for the purpose described, 60 a glue-pot, a steam-supply pipe for said glue-pot, a take-up roller mounted to rotate with its periphery in said glue-pot, a hollow roller above said take-up roller and arranged for engagement with the latter and tubular side arms having their forward ends journaled in 65 said hollow roller, the rear ends of said arms having a swing-joint connection with a branch pipe leading from the steam-supply pipe, as set forth.

7. In a machine for the purpose described, 70 the combination with the gluing devices, of a support for the paper after it has left said gluing devices, said support comprising a horizontal rack formed of uprights, side bars 75 removably resting on said uprights, and cross-bars connecting said side bars, as set forth.

8. In a machine for the purpose described, 80 the combination with the gluing-rollers, of standards located adjacent said rollers, cross-bars connecting said standards, and a series of fingers secured to each cross-bar and arranged to receive the paper between them as it passes between the said rollers, as set forth.
